US0D1019427S

(12) **United States Design Patent** (10) Patent No.: **US D1,019,427 S**
(45) Date of Patent: ** Mar. 26, 2024

(54) **TEMPERATURE AND LUMINOSITY SENSOR**

(71) Applicant: **SOMFY ACTIVITES SA**, Cluses (FR)

(72) Inventor: **François Duchosal**, Annecy (FR)

(**) Term: **15 Years**

(21) Appl. No.: **35/516,361**

(22) Filed: **Dec. 10, 2021**

(80) **Hague Agreement Data**

Int. Filing Date: **Dec. 10, 2021**

Int. Reg. No.: **DM/217875**

Int. Reg. Date: **Dec. 10, 2021**

Int. Reg. Pub. Date: **Jun. 10, 2022**

(51) **LOC (14) Cl. 10-04**

(52) **U.S. Cl.**

USPC **D10/53**

(57) **CLAIM**

The ornamental design for a temperature and luminosity sensor, as shown and described.

DESCRIPTION

1. Temperature and luminosity sensor

1.1 : Perspective

1.2 : Front

1.3 : Back

1.4 : Right

1.5 : Left

1.6 : Top

1.7 : Bottom
